UNITED STATES PATENT OFFICE.

LOUIS WOLDEMAR RAVENÉZ, OF PARIS, FRANCE, ASSIGNOR TO THE SOCIÉTÉ NOUVELLE DES ÉTABLISSEMENTS DECAUVILLE ÀINÉ, OF SAME PLACE.

ELECTRIC IGNITION DEVICE FOR INTERNAL-COMBUSTION ENGINES.

SPECIFICATION forming part of Letters Patent No. 613,309, dated November 1, 1898.

Application filed March 7, 1898. Serial No. 672,983. (No model.)

To all whom it may concern:

Be it known that I, LOUIS WOLDEMAR RAVENÉZ, a citizen of the Republic of France, residing at Paris, France, have invented certain new and useful Improvements in or Relating to Electric Ignition Devices for Internal-Combustion Engines, of which the following is a specification.

This invention relates to electric ignition devices for internal-combustion engines; and it consists, chiefly, of a platinum wire maintained in an incandescent state by means of an electric current and arranged so that its position relatively to the explosion-chamber can be adjusted as desired for the purpose of enabling the working of the motor to be regulated by advancing or retarding the period of ignition.

An ignition device according to the present invention is illustrated, by way of example, in the accompanying drawings, in which—

Figure 1 is a side elevation, and Fig. 2 a front elevation in vertical section.

The device according to the present invention is mainly constituted by a rod A, consisting of an insulating core or filling B, surrounded by a copper sheath C, level with its lower end, but stopping a little below its upper end. The core B is covered by a cap D, provided with a terminal F. A conductor G passes through the whole length of the core B and terminates at the upper end at the terminal F and projects at the lower end to a sufficient extent below said core. Another conductor H, connected at the bottom to the copper sheath C, forms its continuation to the same length as the end of the wire G. The corresponding ends of the wires G and H are connected by a platinum wire I, destined to be rendered incandescent. Thus constituted the ignition device A is arranged on the cap J or end of the cylinder in which it is to ignite the explosive mixture. To this end it is mounted in a stuffing-box on the cap J and having its passage L, forming a continuation of the passage M of said cap J, communicating with the explosion-chamber N, with which also communicate tubes O P of the inlet and exhaust valves, respectively. The rod A passes through the stuffing-box K,

so that it can freely slide up and down in the latter, while the joint is maintained air-tight. In this way the position of the incandescent wire I relatively to the explosion-chamber can be regulated.

The movement of the rod A is effected by hand by means of a lever Q, the pin of which is operated by a handle arranged in a suitable position within reach of the operator or attendant through a system of levers R S, the lever S being pivoted about a fixed point T, its bifurcated portion U being connected, by means of hinged rods V, to a ring W, with trunnions or pins X, secured to the upper end of the sheath C.

The manner of operating the ignition device described is as follows: The circuit of an electric current, supplied, say, by an accumulator, having been formed by the contact F, to which one of the wires is connected, and by the sheath C and motor, to which the other wire of the circuit is connected, the platinum wire I is rendered and maintained incandescent. According to whether it is desired to produce the explosion sooner or later relatively to the admission and compression of the charge the wire I is moved relatively to the explosion-chamber by moving the rod A, so as to effect when brought nearer an earlier ignition and when moved away a later ignition of the charge.

It will be understood that instead of being regulated by hand the position of the rod A could be regulated automatically by the action of any suitable regulating device combined so as to insure the speed of the motor being regulated under the most favorable conditions.

I claim—

1. An electric ignition device for internal-combustion engines comprising a movable rod guided in a stuffing-box on the cylinder, said rod consisting of a conducting-wire and insulating-core surrounded by a metallic sheath the sheath having a wire attached to its lower end the two wires being connected together at their ends below the stuffing-box by a platinum wire the platinum wire being adapted owing to the adjustability of the movable rod to be moved nearer to or farther

away from the explosion-chamber for the purpose of altering the time of ignition of the explosive mixture substantially as described.

2. An electric ignition device for internal-combustion engines comprising a conducting-wire G in an insulating-core B provided with a metallic sheath C having a depending wire H, the ends of the wires G H being connected by a platinum wire I, the whole being adjustable in a stuffing-box secured to the wall

of the cylinder, and means for adjusting the position of said ignition device as set forth.

In testimony whereof I have hereto set my hand in the presence of the two subscribing witnesses.

LOUIS WOLDEMAR RAVENÉZ.

Witnesses:

LOUIS SALLIGER,
EDWARD P. MACLEAN.
